UNITED STATES PATENT OFFICE.

OTTO GESSLER, OF DETROIT, MICHIGAN.

SASH LIFTER.

Application filed September 17, 1925. Serial No. 56,851.

This invention relates to sash and window raising mechanism through the medium of which the raising and lowering of windows as in automobiles is effected, and has for 5 its object to provide novel clutching means whereby the lowering or falling of the window or sash other than when the mechanism is deliberately operated for that purpose is prevented, and the maintenance of the window or sash in any elevated adjustment 10 is insured.

There are a number of mechanisms accomplishing this purpose, but usually these are of a more or less complicated nature, 15 expensive to manufacture, difficult to install, or lacking in durability, often as a result of the incorporation in the clutching means of springs upon which dependence is placed for the clutching operation.

20 The present invention contemplates the avoidance of the use of springs in the clutching mechanism; and the provision of means operable by the weight of the window or sash against descent by its own weight, and 25 of manually operable means whereby the sash raising mechanism may be actuated by the raising or lowering of the sash, said manually operable means also effecting the 30 declutching of the clutch device.

Further objects subsidiary to or resulting from the aforesaid objects, or from the construction or operation of the invention as it may be carried into effect, will become apparent as the said invention is hereinafter 35 further disclosed.

In carrying the said invention into effect I may provide, for the raising or lowering 40 of a window or device, a rotary gear having a lifting arm attached thereto for the raising and lowering of the said window as said gear is revolved in one direction or the other, and a pinion adapted to manual rotation for the revolving of the said gear, 45 said pinion being associated with a clutch mechanism through which said pinion may be freely operated manually and which is brought into a clutching condition if the rotation of said pinion be effected by said

gear whereby such rotation of the pinion 50 by said gear is checked and the continued movement of the gear prevented.

The clutch may comprise a ring or housing within which a pair of braking members are rotatable, said members being movable 55 relatively into and out of engagement with said housing, the inward disengaging movement thereof being effected by a manually operable device through which rotary motion is transmitted to said members, said 60 pinion having abutments whereby the rotary motion of said members is transmitted to said pinion for the operation of said gear; and the abutments of said pinion are adapted upon rotation of said pinion by said gear 65 to effect the outward movement of said members into engagement with said housing.

All of which is more particularly described and ascertained hereinafter, by way of example, having reference to the accompanying drawings, wherein—

Figure 1 is a fragmentary elevation of an automobile door with part of one of the walls thereof broken away to disclose the adaptation of my improved sash raising device 75 thereto;

Figure 2 is a transverse section taken on the line 2^x—2^x, Figure 1;

Figure 3 is a fragmentary detail elevation of the said mechanism;

Figure 4 is a transverse section of the same taken on the line 4^x—4^x, Figure 3;

Figure 5 is a section taken on the line 5^x—5^x, Figure 4;

Figure 6 is a detail sectional view of the 85 clutch mechanism taken on the line 6^x—6^x, Figure 4;

Figure 7 is a detail elevation of the pinion removed;

Figure 8 is a detail elevation of the clutch 90 releasing member;

Figure 9 is a similar view to Figure 3 showing a modified form of the device in its locked condition;

Figure 10 is a similar view to Figure 4 of 95 such modified form;

Figure 11 is a sectional elevation of the clutch taken on the line 11^x—11^x, Figure 10;

Figure 12 is a detail perspective view of the modified form of clutch releasing member; and

Figure 13 is a perspective view of the 5 brake members removed.

Similar characters of reference indicate similar parts in the several figures of the drawings.

1 indicates a door structure wherein is 10 mounted a vertically slidably window 2 and a rotatable gear 3 provided with an arm 4, the extremity 5 of which has roller contact with the underside of the window whereby the said window may be raised and lowered 15 by the rotation of the said gear 3 in one or other direction. As the method by which the actual operation of the window is effected by the said gear is not essential to this invention and lends itself to use with many 20 different mechanical arrangements for actually lifting and lowering a window, further description of this part of the device is not entered into herein, except to explain that in the illustrated arrangement the said gear 25 3 is rotatable on a supporting plate 6 suitably attached within the structure of the door 1, and is provided with a spring 7 acting more or less as a counterbalance for the window and attached at its outer end to a 30 pin 8 carried by the plate 6, which pin projects through an arcuate slot 9 in the gear and acts as a stop, limiting the extent to which the said gear may rotate.

10 is an operating crank for effecting the 35 rotation of the gear 3 in one or other direction by means of a pinion 11 to which the said crank is indirectly connected as will be further explained, and this crank has a spindle 12 which passes through an opening 13 40 in the plate 6 above the gear 3, the inner projecting end 14 of the said spindle being cut away or flattened as at 15 on opposite sides thereof to within a short distance of the said plate.

45 Upon the uncut portion of the spindle extending through the said plate the pinion 11 is freely mounted in mesh with the gear 3 and the plate is provided with a raised portion 16 about the said pinion 11 to form a 50 support for a disk 17 secured thereto by screws 18, which disk extends over the face of the said pinion and partially over the face of the gear 3, and is provided with a central opening 19 of greater diameter than the spindle 12. The said opening admits of 55 the projection of centrally disposed abutments 20 on the said pinion through said opening, so that they extend into a central recess 21 formed in the face of the said disk 60 17.

65 The disk 17 forms the fixed member or housing of a clutch device which also includes movable members or brakes 22 and 23 rotatable in said recess 21 and a clutch releasing and rotating member 24 mounted on

the flattened portion 14 of the spindle 12, the said member 24 having an elongated central orifice 25 conforming to the cross sectional shape of the flattened portion 14 of the spindle and ensuring the rotation of the said member 24 with the said spindle. The clutch releasing member is provided at its extremities with abutments 26 and 27 which enter openings or recesses 28 and 29 in the said movable members 22 and 23 respectively.

70 It will be noted that the member 22 is provided with a tongue 22^a slidably entering a complementary slot 23^a in the member 23, and that the abutments 26 and 27 of the clutch releasing member are adapted to engage the innermost faces of the recesses or slots 28 and 29 if the said clutch releasing member be rotated slightly relevant to the members 22 and 23, thereby drawing the said members 22 and 23 together towards the axis of the spindle.

75 These members 22 and 23 are provided with outer corners or friction points 22^b and 23^b, which may frictionally engage the annular wall of the recess 21, but which are withdrawn from such engagement therewith when the said members 22 and 23 are moved inwardly therefrom by the clutch releasing member; and as this clutch releasing member is definitely rotatable with the spindle 12 upon the operation of the crank 10 it accordingly follows that the members 22 and 23 are retracted from the annular wall of the 80 recess 21 whenever the said crank is operated in any direction. Consequently, upon such operation of the crank, the pinion 11 is freely rotated by reason of the engagement of its abutments 20 in inner recesses 22^c and 23^c in the said members 22 and 23 and the gear 3 also rotated for the raising or lowering of the window.

85 If, however, when the window is raised, its weight tends to perform the reverse 100 operation and cause the gear 3 to revolve the pinion 11, the abutments 20 of the said pinion will press the said members 22 and 23 outwardly so that their friction points will engage the annular wall of the recess 21 of the disk 17, thereby locking the said members 22 and 23 against rotation in the disk and of course preventing further rotation 105 of the pinion 11 by the gear 3. Thus the transmission of power from the crank to the gear for the raising of the window, is effected through the members 22 and 23 simultaneously with the effecting of their inward declutching movement, but in transmitting power in the opposite direction from the gear 3 to the pinion, the said pinion effects the clutching movement of the said members 22 and 23.

110 The simplicity of this construction is very apparent. The clutch mechanism does not 115 call for the use of springs; the pinion, clutch

releasing member, movable clutch members and the fixed clutch member or ring may be stampings, and the machine work required upon the spindle to provide for accommodation of the parts carried thereby amounts to very little.

The clutch releasing member is shown as being surmounted by a washer 30, and a nut 31 over which the end of the spindle is riveted as at 32.

The modified arrangement, Figures 9 to 13 is similar to that already described, but includes a liner or band 33 lining the annular walls of the recess 21 of the disk 17 and which ring 33 is rotatable with the movable members or brakes 22' and 23', the latter of which is shown as being provided with a tongue 34 adapted to enter between inwardly projecting ends 35 of the ring 33 which is split at this point to insure the rotation of the ring with the brake members and thereby protect the brake members and the disk 17 from wear one by the other.

The clutch releasing members 24' are also provided with ear pieces 36, 37, 38 and 39 projecting over the face of the disk 17 and retaining the ring against lateral displacement, and 40 indicates a roller or wedge member which may be disposed between the brake members and the ring 33 as an aid to the clutching effect.

I attach considerable importance to the fact that my construction admits of marked thinness in the clutch which makes it both compact and adapts it to incorporation in very thin doors or structures; and also to the fact that the parts, and especially the pinion, may consist almost entirely of stampings, the lugs 20 of the said pinion being simply formed in the stamping operation.

This invention may be developed within the scope of the following claims without departing from the essential features of the said invention, and it is desired that the specification and drawings be read as merely illustrative and not in a limiting sense, except as necessitated by the prior art.

What I claim is:—

1. In a device of the class described, lifting means, a gear operating said lifting means, a manually rotatable pinion operably meshed with said gear, a clutch comprising a housing, a pair of braking members rotatable therein and movable relatively into and out of engagement with said housing, manually rotatable means effecting the disengagement of said braking members from said housing simultaneously with the transmission of rotary motion (through said members) to said pinion, and means movable by said pinion against said braking members and effecting their engagement with said housing when partial movement of said pinion is effected by said gear.

2. In combination with a meshed driving

pinion, and a gear wherein said gear at times tends to drive said pinion, means effecting the rotation of said pinion for the driving of said gear and prevent its being driven by said gear, said means comprising a clutch mechanism, a spindle operating said pinion through said clutch mechanism, and means on said pinion effecting the clutching operation of said clutch mechanism.

3. In combination with a meshed driving pinion and a gear wherein said gear at times tends to drive said pinion, a clutch including rotatable brake members, said pinion being rotatable with said members and also slightly rotatable relative thereto, means rotating said members for the rotation of said pinion, and means on said pinion effecting the clutching operation of said members when said pinion is rotated relatively thereto.

4. In combination with a meshed driving pinion and a gear wherein said gear at times tends to drive said pinion, an operating spindle passing loosely through said pinion, a clutch including rotatable brake members, said pinion being rotatable with said members, a declutching member rotatable with said spindle and transmitting motion of said spindle through said brake members to said pinion, and brake operating means actuated by said pinion.

5. In combination with a meshed driving pinion and a gear, wherein said gear at times tends to drive said pinion, an operating handle, and a clutch including brake members freely rotatable by said spindle and rotating said pinion, and movable to non-rotatable positions by said pinion, said members being coupled to said pinion whereby its rotation is depended upon and effected through said members.

6. In combination with a meshed driving pinion and a gear, wherein said gear at times tends to drive said pinion, clutch mechanism resisting such tendency and including a fixed housing, and members rotatable therewithin, said pinion being rotatable by said members, and means checking the rotation of said members by said pinion, said means comprising abutments on said pinion engaging said members and moving them to non-rotative positions in said housing.

7. The combination according to claim 6, including a pinion rotating spindle, and a member rotatable with said spindle engaging said members and moving them from a non-rotative to a rotative position upon the rotation of said member by said spindle whereby such rotation is transmitted to said pinion.

8. In a device of the class described, a gear, a pinion, a clutch including a housing and brake members within said housing, means effecting the rotation of said pinion through the medium of said brake members,

1 said means declutching said brake members when rotating said pinion, means actuated by said pinion moving said members to clutched positions upon the partial rotation of said pinion by said gear, and a liner interposed between the brake member and the housing, said liner being rotatable with said brake members and transmitting pressure

thereof against said housing when said members are moved to clutching positions.

9. In a device according to claim 8, retaining means on said declutching means positioning said liner in said housing.

In testimony whereof I affix my signature.

OTTO GESSLER.
